DOOR LATCH STRUCTURE

George Janonis, Detroit, Mich.

Original application July 7, 1941, Serial No. 401,360. Divided and this application November 26, 1941, Serial No. 420,569.

19 Claims. (Cl. 292—219)

This invention relates generally to vehicle door latch structure and constitutes a division of my application filed July 7, 1941, bearing Serial No. 401,360.

One of the essential objects of the invention is to provide an improved latch bolt and keeper therefor that are exceptionally effective to hold the door in partially or fully closed position.

Another object is to provide an improved mounting for said latch bolt.

Another object is to provide a door latch structure that is simple in construction, inexpensive to manufacture, and easy to install.

Other objects, advantages and novel details of construction of this invention will be made more apparent as this description proceeds, especially when considered in connection with the accompanying drawing, wherein:

Figure 1 is a fragmentary elevation of a door and jamb therefor when viewed from the outside of a vehicle body;

Figure 2 is a sectional view taken substantially on the line 2—2 of Figure 1;

Figure 3 is a sectional view taken substantially on the line 3—3 of Figure 1;

Figure 4 is a fragmentary edge elevation of the jamb and showing the keeper mounted thereon.

Referring now to the drawing, A is a hingedly mounted door of a vehicle body, B is a jamb or upright abutment therefor, C is a latch bolt, and D is a keeper for the latch bolt of a latch structure embodying my invention.

As shown, the door A has the inner and outer panels 10 and 11, respectively, and the intermediate supporting uprights 12 to which said panels are rigidly secured. The jamb B may be any suitable construction to limit the closing movement of the door and is preferably a rigid part of the vehicle body.

The latch bolt C is wedge-shaped in configuration and is mounted to swing over the outside free edge of the door. Preferably the head 13 of the wedge-shaped bolt is rounded and has a laterally extending cylindrical shank 14 that extends through the free edge of the door and is journaled in a bearing formed by complementary semi-circular portions 15 and 16, respectively, of case plate sections 17 and 18 upon the inside and rigid with the free edge of the door. Such sections 17 and 18 are preferably L-shape in cross section and are secured to each other as well as to the free edge of the door. Preferably the webs 19 and 20, respectively, of said sections are secured together in back-to-back rela-

tion while the lateral flanges 21 and 22 of said sections are secured to the door.

The keeper D for the bolt C has a J-shaped portion 23 disposed edgewise on and rigid with an attaching plate 24 that in turn is rigid with the jamb B and is provided on the inner face of the J at the free edge of the shank 25 thereof with two steps 26 and 27, respectively, adapted to be successively engaged by the latch bolt C. Preferably these steps 26 and 27 are integral with the J-shaped portion 23. In fact, the free end of the shank 25 is inclined so as to be flush with and form a part of the first step 26. Any suitable means such as the screws 28 may be used to secure the plate 24 to the jamb B.

In the present instance, the latch bolt C is operated from the inside and outside of the door by two remote control means E and F, respectively, as set forth in my application Serial No. 401,360. Preferably such remote control means are operatively connected to the shank 14 of the bolt by pins 30 and 31, respectively, projecting from diametrically opposite sides of said shank. Coil springs 32 and 33 extend in opposite directions from said pins 30 and 31 and are connected by bolts 34 and 35 anchored in the webs 19 and 20 of the case plate sections 17 and 18 for normally retaining the tapered tail 36 of the latch bolt in lowered keeper engaging position.

The remote control means E operable from the inner side of the door preferably comprises a relatively long lever 47 pivoted substantially midway its ends on a bracket 48 fixed to the inner panel 10 of the door and having one end portion 49 movable in a slot 50 in the case plate section 17 for engagement with the pin 30 on the latch bolt shank 14, a relatively short lever 51 also pivoted substantially midway its ends on the bracket 48 and having a pin 52 engaging a longitudinally extending slot 53 in the adjacent end of the long lever 47, a bell crank lever 54 pivoted at the juncture of the arms 55 and 56 thereof upon a plate 57 rigid with the inner panel 10 of the door, a long link 58 terminally connected to the short lever 51 and to the arm 55 of the bell crank lever 54, a hand lever 59 pivoted adjacent one end to the plate 57, and a short link 62 terminally connected to the hand lever 59 and arm 56 of the bell crank lever 54.

Thus, by pulling outwardly the free end 71 of the hand lever 59, the bell crank lever 54, link 58 and levers 51 and 47 will cause the pin 30 to be depressed so that the latch bolt C will be retracted against the tension of the springs 32 and 33. In this connection, it will be noted that

the engagement of the long lever 41 with the pin 39 on the bolt shank 14 is such that the bolt C is free to turn independently of the inside remote control means E when, for example, the door is slammed or pulled to closed position.

The remote control means F operable from the outer side of the door comprises an upright hand lever 73 disposed substantially parallel to and pivoted at its lower end upon an elongated bracket 14 rigid with the inside of the free edge of the door, a substantially T-shaped pin 75 rigid with said hand lever below and slightly offset relative to the pivot 76 for said hand lever, and a long link 77 terminally connected to the T-shaped pin 75 and to the pin 31 on the shank 14 of the latch bolt. As shown, this link 77 has an elongated slot 78 receiving the pin 31 on the bolt shank so that the latter and pin 31 may move independently of the outside control means F when the door is slammed or pushed to closed position, and has an opening 79 receiving the stem 80 of the T-shaped pin 75 on the hand lever 73. Preferably a finger piece 81 is provided on the outer side of the hand lever 73 at its upper free end to facilitate movement thereof by an operator. Thus, when the upper free end of the hand lever 73 is pulled outwardly, the link 77 will lift the pin 31 and thus cause the latch bolt C to be retracted against the tension of the springs 32 and 33.

What I claim as my invention is:

1. A door latch structure comprising a pair of case plate sections having complementary semi-circular portions forming a bearing, a substantially wedge-shaped latch bolt adjacent said sections, the head of the wedge being rounded and having a laterally projecting substantially cylindrical portion journaled in the bearing aforesaid, a keeper for the latch bolt having a substantially J-shaped portion, the curved part of the J being adapted to receive the rounded head of the latch bolt, the shank of the J being provided upon its inner face in spaced relation to said curved part with two steps arranged in tandem and adapted to be successively engaged by the tapered end of the wedge-shaped latch bolt, the laterally projecting cylindrical portion of the latch bolt having projections at substantially diametrically opposite points thereof, and oppositely extending yieldable means terminally connected to said projections and case plate sections and normally retaining the tapered end aforesaid of the wedge-shaped bolt in engagement with one of the steps aforesaid of said keeper.

2. A door latch structure comprising a pair of case plate sections having complementary semi-circular portions forming a bearing, a substantially wedge-shaped latch bolt adjacent said sections, the head of the wedge being rounded and having a laterally projecting substantially cylindrical portion journaled in the bearing aforesaid, and a keeper for the latch bolt having a substantially J-shaped portion, the curved part of the J being adapted to receive the rounded head of the latch bolt, the shank of the J being provided upon its inner face in spaced relation to said curved part with two steps arranged in tandem and adapted to be successively engaged by the tapered end of the wedge-shaped latch bolt.

3. A door latch structure comprising a pair of case plate sections having complementary semi-circular portions forming a bearing, a substantially wedge-shaped latch bolt adjacent said sections, the head of the wedge being rounded and

having a laterally projecting substantially cylindrical portion journaled in the bearing aforesaid, the laterally projecting cylindrical portion of the latch bolt having projections at substantially diametrically opposite points thereof, and oppositely extending yieldable means terminally connected to said projections and case plate sections and normally retaining the tapered end aforesaid of the wedge-shaped bolt in a predetermined position.

4. A door latch structure comprising a pivotally mounted latch bolt having a wedge-shaped portion, and a keeper for said latch bolt having a substantially J-shaped portion for receiving the wedge-shaped portion of the bolt and having two steps on the inner side of the shank of the J at the free end thereof successively engageable by the wedge-shaped portion of the bolt.

5. A door latch structure comprising a pivotally mounted latch bolt, and a keeper therefor, the latch bolt being wedge-shaped in configuration, the head of the wedge being rounded and having a laterally projecting substantially cylindrical portion constituting the pivot element of the latch bolt, and the keeper having an attaching plate and a substantially J-shaped portion disposed edgewise on and rigid with one side of said plate, the curved part of the J being adapted to receive the rounded head of the latch bolt, and the shank of the J being provided upon its inner face in spaced relation to said curved part with two steps arranged in tandem and adapted to be successively engaged by the tapered end of the wedge-shaped latch bolt.

6. A door latch structure having a pivotally mounted latch bolt, and a keeper for said latch bolt, the latch bolt being wedge-shaped in configuration, the head of the wedge being rounded and having a laterally projecting substantially cylindrical portion constituting the pivot element of the latch bolt, the keeper having a substantially J-shaped portion adapted to receive the wedge-shaped latch bolt, the curved part of the J being adapted to receive the rounded head of the latch bolt, and the shank of the J being provided upon its inner face in spaced relation to said curved part with steps arranged in tandem and adapted to be successively engaged by the tapered end of the wedge-shaped latch bolt.

7. A door latch structure having a pivotally mounted wedge-shaped latch bolt, and a keeper for said latch bolt having an attaching plate and a substantially J-shaped portion disposed edgewise on and rigid with one side of said plate, the curved part of the J being adapted to receive the head of the wedge-shaped latch bolt, and the shank of the J being provided upon its inner face in spaced relation to said curved part with two steps arranged in tandem and adapted to be successively engaged by the tapered end of the wedge-shaped latch bolt.

8. A door latch structure comprising a pivotally mounted latch bolt having a substantially wedge-shaped portion, and a keeper for the wedge-shaped portion of the latch bolt having a substantially J-shaped portion, the curved part of the J being adapted to receive the head of the wedge-shaped portion of the latch bolt, the shank of the J being provided upon its inner face in spaced relation to said curved part with two steps arranged in tandem and adapted to be successively engaged by the tapered end of the wedge-shaped portion of the latch bolt.

9. A door latch structure comprising a latch bolt having a substantially wedge-shaped por-

tion, and having a laterally projecting substantially cylindrical portion constituting the pivot element of the latch bolt, a keeper for the wedge-shaped portion of the latch bolt having a substantially J-shaped portion, the curved part of the J being adapted to receive the head of the wedge-shaped portion of the latch bolt, the shank of the J being provided upon its inner face in spaced relation to said curved part with two steps arranged in tandem and adapted to be successively engaged by the tapered end of the wedge-shaped portion of the latch bolt, the laterally projecting cylindrical portion of the latch bolt having projections at substantially diametrically opposite sides thereof and yieldable means connected to said projections and normally retaining the tapered end aforesaid of the

wedge-shaped portion of the bolt in engagement with one of the steps aforesaid of said keeper.

10. A door latch structure having a pivotally mounted latch bolt provided with a wedge-shaped portion, and a keeper for the wedge-shaped portion of the latch bolt having an attaching plate and a substantially J-shaped portion carried by said plate, the curved part of the J being adapted to receive the head of the wedge-shaped portion of the latch bolt, and the shank of the J being provided upon its inner face in spaced relation to said curved part with two steps arranged in tandem and adapted to be successively engaged by the tapered end of the wedge-shaped portion of the latch bolt.

GEORGE JANONIS.
